JAMES PETERSON, OF PRICE, UTAH.

FOLDING UMBRELLA.

1,031,868.

Specification of Letters Patent.

Patented July 9, 1912.

Application filed June 6, 1911. Serial No. 631,610.

To all whom it may concern:

Be it known that I, JAMES PETERSON, a citizen of the United States, residing at Price, in the county of Carbon and State 5 of Utah, have invented certain new and useful Improvements in Folding Umbrellas, of which the following is a specification.

The purpose of my invention is to provide an umbrella that may be used as an 10 ordinary umbrella and by a slight manipulation of some of the parts may be folded into compact form for placing in a grip, suit case or other receptacle, and one that is suitably and strongly braced. These 15 objects I accomplish with the device illustrated in the accompanying drawings in which similar letters of reference indicate like parts throughout the several figures.

Figure 1 is a vertical section of the umbrella when extended and cover removed, parts cut away. Fig. 2 is an elevation of the umbrella folded with the cover removed and parts cut away. Fig. 3 is an elevation of a portion of the staff. Fig. 4 is an elevation of the link tube. Fig. 5 is a plan of the upper runner. Fig. 6 is a side elevation of same. Fig. 7 is a plan of the lower runner. Fig. 8 is a side elevation of the same. Fig. 9 is a plan view of the 20 upper end of a portion of the staff. Fig. 10 is a side elevation of the same. Fig. 11 is a side elevation of the upper portion of the staff with one of the spring catches shown extended and as flexed in dotted 25 lines. Fig. 12 is a plan view of the cam sleeve and a section of the lower runner.

In the drawings the upper portion of the staff is rod 1, and this part of the staff fits closely and telescopes within the other 30 portion, a tube 2, of the staff. The rod 1 has a spring catch 3 secured near the middle thereof and carries a notched and channeled bearing 15 thereon near the upper end. Said rod 1 also has another spring 35 catch 4 thereon and a catch opening 5 thereinto. The said tube 2 has the segment of an extended flange 6 on its upper end and a longitudinal slot 7 cut thereinto. The upper end of said slot 7 has a section 8 thereof 40 formed wider, and opening into the said widened part 8 is cut a short slot 9 parallel with the said slot 7. Near its lower end the said slot 7 is also cut wider forming a set off 10 in the other side of said slot 7. The 45 said slots 7, 8, 9 and 10 are cut to receive the said spring catch 3, when and as de-

sired in the manipulation of the umbrella. Slidably carried on the said tube 2 is the upper runner 11, which has a portion thereof longitudinally extended and bent radially inward forming a lug 12. The said lug 12 is made to engage the said segment flange 6, when they are adjacent, to lock the said runner 11 and said tube 2 together from independent longitudinal movements. 60 To the said upper runner 11 is pivoted the inner ends of a plurality of stretchers 13, which set of stretchers have their outer ends pivoted to the ribs at the joint 14 therein. Said ribs are severed and hingedly connected at said joint 14. The inner sections 16 of said ribs are pivoted to said notched bearing 15. Also carried on said tube 2 is the lower runner 17, which has secured thereon a catch 18. This catch 18 is made 70 to engage in the catch opening 5 within the rod 1, to lock the lower runner 17 and the said rod 1 together which is done to fold the umbrella, but does not so engage when the umbrella is collapsed or used as 75 an ordinary umbrella. Said catch 18 has a longitudinal notch 25 cut in its lower end. To the said lower runner 17 is pivoted the inner ends of another set of stretchers 19, which have their upper ends pivoted to 80 the outer sections 20 of said ribs. On the upper portion of said runner 17 is formed a longitudinally extended lug 21 made to engage in a notch 22 in the lower end of the upper runner. The purpose being to lock 85 the two runners together when they are adjacent to prevent any tendency of independent axial movement. The said runner 17 carries thereon a cam sleeve 23, which sleeve has secured therein a cam 24 made 90 to operate within the said notch 25 in the lower end of the said catch 18. Also within the peripheric face of said sleeve 23 are 95 cut two openings 37. Secured on said lower runner 17 and within the said sleeve 23 is the spring catch 26, the point of which is made to operate within the said openings 37 in the peripheric face of said sleeve 23, to prevent unintentional movement of said 100 sleeve. Within the lower end of the said tube 2 is securely fitted an axial lug 27 having thereon a radially extended lug 29, to the lug 27 is fastened one link of a chain 28. Said chain is preferably made up of three or four links, and is attached to one 105 end of the link tube 32. Said link tube has a diametrical longitudinally disposed

opening 31 therein, within which opening is operated a guide pin 32' the ends of which seat and are secured in the tube 2', hereinafter more fully described. Also 5 within and to said link tube 32 is fastened the spring catch 33, which engages in slots cut in the surrounding tube 2'. To the lower end of said link tube is fastened one end of a spiral spring 34, the other end of 10 which is secured to the lower end of said tube 2'. Slidably telescoping over the said link tube 32 is the lower portion of the staff of the umbrella formed as a tube 2' hereinbefore mentioned and having an open longitudinal cut 30 in its upper end. Said 15 cut is made to engage the said lug 29 to prevent axial turning when so engaging. Said tube 2' has two longitudinally aligned spring catch openings 35 and 35' in its side, 20 within which the said spring catch 33 engages and the operation of the pin 32' in the opening 32 insures the catch 33 to be in the same radial plane as the openings 35 and 35'. Fitted on the lower end of 25 said tube 2' is the hand hold 36.

When assembled as shown in Fig. 1, the rod 1 and the tube 2 are locked together by the catch 3 engaging in the opening 8 in said tube 2, the tubes 2 and 2' are locked together by the spring catch 33 engaging in the opening 35', while at the same time the lug 27 is telescoped within the upper end of said tube 2'. When in this position the pressing in of the spring catch 4 will allow 35 the umbrella to collapse or close as any ordinary umbrella. By sliding the lower runner upward on the said tube 2 until the said runner passes over the said catch 4 the umbrella is extended as shown in Fig. 1. To 40 fold the umbrella, the cam sleeve 23 is firmly held, preferably with the left hand, and with the other hand grasping the hand hold 36 the umbrella is given a slight axial turn. When the umbrella is extended the upper 45 runner 11 presses the spring catch 3 from its engagement in the slot 9, and this axial turning will allow the tube 2 to turn axially far enough to engage the said catch 3 in the slot 7 and in this position the segment flange 50 6 is thrown into engagement with the lug 12. A continuation of said axial turn of all of the umbrella except the said cam sleeve, will move the catch 18 on the cam 24, and this in turn will cause the engagement of 55 the said catch 18 in the opening 5 of the said rod 1 through the opening 39 in the runner 17, and lock the said runner to the rod 1. By then sliding the said lower runner 17 longitudinally downward on the tube 2 the 60 umbrella is folded except the lower portion of the staff. Then by depressing the spring catch 33 and pulling longitudinally on the hand hold 36 the said catch 33 is withdrawn from its engagement in the opening 35' and 65 made to engage in the opening 35. When

the longitudinal pull on the hand hold has drawn the spring catch 33 into the opening 35 and the said pull released the tension of the chain is released and the tube 2' portion of the staff may be doubled back parallel 70 with the tube 2.

Having thus described my invention, I desire to secure by Letters Patent and claim:—

1. A folding umbrella comprising a rod having a catch opening therein, two spring 75 catches secured thereto, a notched bearing carried thereon near the upper end, a tube within which said rod is telescoped and in the side of which is a longitudinal slot having portions thereof widened, a segment 80 flange on the upper end of said tube, a runner carried on said tube, a lug on said runner adapted at times to engage said segment flange, sectioned and hingedly connected ribs pivoted to said notched bearing, a plurality of stretchers pivoted to said runner and to said ribs at the hinged joint of said ribs, a notch in the lower edge of said runner, a lower runner also carried on said tube having a lug thereon which at times engages 85 in the said notch in the said upper runner, a catch carried on said lower runner adapted to engage at times within the opening in said rod, and having an open slot in the lower end thereof, another set of stretchers 90 pivoted to said lower runner and to the outer section of said ribs, a cam sleeve carried on said lower runner having openings in its peripheric face, a cam carried within said sleeve adapted to engage within the 100 open slot in said catch, a spring catch secured to said lower runner within said sleeve and adapted to engage within the openings in the peripheric face of said sleeve, and another tube detachably secured to said first 105 mentioned tube.

2. A folding umbrella comprising telescoping staff sections, slidably movable runners carried on the outer of said sections, catch openings in the sides of said staff sections adjacent the runners on said staff when the umbrella is extended and with the openings in the inner section of said staff registering with the openings in the outer section of said staff when the umbrella is so extended, severed and hingedly connected ribs pivoted to said staff, stretchers pivoted to said ribs and to said runners, a catch carried on the lower of said runners and adapted to operate through one of the openings in the 110 outer section of said staff and at times to engage in one of the openings in the inner section of said staff, a cam sleeve carried on the lower runner, and a cam therein adapted to engage said last mentioned catch to withdraw it from engagement with the said inner section of said staff.

3. An umbrella comprising a staff, a runner carried on said staff, a catch opening through the side thereof, a catch pivoted to 130

said runner having a part thereof radially extended and with an open slot in the lower end of said catch, a cam sleeve carried on said runner, a cam carried within said sleeve and made to operate within said open slot and adapted to move said catch on its pivot, and means to hold said sleeve from unintentional rotation.

4. A folding umbrella consisting of a telescoping staff, slidably movable runners carried thereon, catch openings in the sides of said staff adjacent the said runners on said staff when the umbrella is extended, and with the openings in the inner staff registering with the openings in the outer staff when the umbrella is so extended, sectioned and hingedly connected ribs pivoted to said staff, means on the upper of said runners for engagement with the outer section of said staff, stretchers pivoted to said runners and to said ribs, a catch carried in the lower of said runners adapted to lock said runner and the inner section of said staff together and having an open longitudinal slot in the end thereof, a cam sleeve carried on said lower runner, a cam therein adapted to engage in the slot in the end of said catch, a portion of the side of the outer section of said telescoping staff cut out between two of the catch openings therein to form a longitudinal slot within which slot a catch fastened to the inner section of said telescoping staff is operated, and a spring catch adapted to hold said umbrella ex-

tended when in engagement with said lower runner.

5. A folding umbrella consisting of a sectioned staff adapted to telescope and having in the side of said staff catch openings near the lower end of the inner section of said staff registering with one of the openings near the middle of the outer section of said staff and one of the openings near the upper end of the said outer section of said staff registering with one of said openings near the middle of said inner section when the staff is extended, and two of said openings in said outer section of said staff connected by a longitudinal slot, severed and hingedly connected ribs pivoted to said staff, runners carried on said staff, an opening in the lower of said runners, stretchers pivoted to said ribs and to said runners, a catch carried on the lower of said runners and made to operate through the said opening therein and adapted to engage in one of the openings in the inner section of said staff, and means carried on said last mentioned runner to withdraw it from its engagement with said inner section of said staff.

In testimony whereof I have affixed my signature in presence of two witnesses.

JAMES PETERSON.
